UNITED STATES PATENT OFFICE.

LOUIS KYLE WOODARD, OF MOUNT VERNON, NEW YORK.

DESIGN FOR A RADIATOR-CAP ORNAMENT.

58,283.

Specification for Design.

Patented June 28, 1921.

Application filed April 1, 1921. Serial No. 457,825. Term of patent 3½ years.

To all whom it may concern:

Be it known that I, LOUIS K. WOODARD, a citizen of the United States, and resident of Mount Vernon, in the county of Westchester and State of New York, have invented a new, original, and ornamental Design for a Radiator-Cap Ornament, of which the following is a specification, reference being had to the accompanying drawing, forming part thereof.

The figure is a perspective view of a radiator cap ornament showing my new design.

I claim:

The ornamental design for a radiator cap ornament as shown.

LOUIS KYLE WOODARD.
